COMBINED MICROFICHE RETRIEVAL AND VIEWER UNIT

Andrew Virgil McClare, Rochester, N.Y., assignor to
Eastman Kodak Company, Rochester, N.Y.

Filed May 17, 1972, Ser. No. 254,344

Term of patent 14 years

Int. Cl. D16—02

U.S. Cl. D61—1 N

FIG. 1

FIG. 2

FIG. 1 is a top, left side, and front perspective view of a combined microfiche retrieval and viewer unit showing my new design;

FIG. 2 is a bottom, right side, and rear perspective view thereof.

I claim:

The ornamental design for a combined microfiche retrieval and viewer unit, as shown.
